(57) **CLAIM**

The ornamental design for a removable baby-seat cover as shown and described.

DESCRIPTION

FIG. 1 is a perspective view looking from the top front right of the removable baby-seat cover showing my new design installed on a typical baby-seat or high chair;

FIG. 2 is a front elevational view thereof;

FIG. 3 is a rear elevational view thereof;

FIG. 4 is a side elevational view thereof;

FIG. 5 is a top plan view thereof.

FIG. 6 is a rear elevational view of the cover as it looks when not installed on a baby-seat or high chair;

FIG. 7 is a front elevational view thereof.

FIG. 8 is a perspective view looking from the top front right of the removable baby-seat cover showing an alternative design of the cover with the only difference being the trim installed on a typical baby-seat or high chair;

FIG. 9 is a front elevational view thereof;

FIG. 10 is a rear elevational view thereof;

FIG. 11 is a side elevational view thereof; and,

FIG. 12 is a top plan view thereof.

The broken lines showing the baby-seat, the belt-strap, and the product tag are for illustrative purposes only and form no part of the claimed design.
